IMPEDANCE COUPLED AMPLIFIER

Arthur C. Stocker, Haddon Heights, N. J., assignor to Radio Corporation of America, a corporation of Delaware

Application December 31, 1936, Serial No. 118,630

12 Claims. (Cl. 179—171)

The present invention relates to resistance-capacity or impedance coupled amplifier for amplifying signals in a relatively wide frequency band.

5 The invention relates more particularly to resistance-capacity coupling networks for amplifiers, as shown in my United States Patent 2,045,316, wherein the signal may vary in frequency between relatively wide frequency limits, 10 such, for example, as from 20 cycles or lower to one megacycle.

In the system referred to, a resistance-capacity coupling network may comprise an output anode circuit for an amplifier tube comprising two branches, one of which includes an output anode coupling resistor and a filter capacitor in series relation to each other and to the anode circuit, and the other of said branches including a coupling capacitor and a load or grid resistor in series relation to each other, the said coupling elements and filter elements having a predetermined relation for improving the low frequency response of the amplifier provided with such network, and in accordance with the equation

$$25 \quad C_g R_g = R_p C_f$$

where

C_g =capacity of the coupling capacitor

R_g =load resistance

30 R_p =resistance of the anode coupling resistor

C_f =capacity of the filter capacitor

The operation of a circuit of that character depends upon loss of gain due to the reactance 35 of the coupling capacitor becoming comparable to the resistance of the grid or load resistor, which is compensated by an equal rise in gain due to the reactance of the filter capacitor becoming comparable to the resistance of the anode circuit resistor.

40 Since a bypass or filter capacitor and filter resistor is employed in wide range amplifiers to reduce the liability of oscillation because of coupling in the common impedance of the anode voltage supply source, it is desirable to so choose

45 the values of the filter capacitor and resistance, that by means of compensation, a relatively low capacity value may be provided in the coupling capacitor. Because of the improved low frequency response in an audio frequency amplifier,

50 the gain may be relatively high below 10 cycles per second, and this gives rise to undesirable response in the amplifier, known as "breathing."

It is, therefore, an object of the present invention, to lower the gain, below a certain predeter-

mined critical frequency in an amplifier interstage resistance-capacity coupling network, without impairing the gain above the predetermined frequency.

5 Heretofore if an attempt is made to lower the low frequency gain below the predetermined limit or critical frequency, by increasing the value of the bypass or filter capacitor, or by lowering the capacity of the coupling capacitor in one or more stages of an amplifier, the gain becomes too low at and above the critical frequency.

10 It is also a further object of the present invention to provide an improved interstage resistance-capacity coupling network providing a relatively high amplifier gain at frequencies within an extended frequency range which may have a response characteristic below a predetermined frequency gradually falling while above the predetermined frequency it may have a response 15 characteristic which may remain substantially flat or otherwise as desired.

20 In applying compensation devices to a resistance-capacity network as an interstage coupling means for an audio frequency amplifier, it has been found that advantage may be taken of the 25 anode circuit filter comprising a series impedance or resistor and a bypass circuit, the compensation being obtained in the bypass circuit.

25 Accordingly, it is an object of the present invention to provide an interstage coupling network of the resistance-capacity type, having a filter in the input or anode coupling portion thereof provided with a bypass circuit, the capacitive reactance of which is relatively low below a certain predetermined low frequency, and the capacitive reactance of which above such predetermined frequency is relatively high. In an audio frequency amplifier, this low frequency may be in the range below 100 cycles per second.

30 The invention will, however, be better understood from the following description when considered in connection with the accompanying drawing and its scope will be pointed out in the appended claims.

35 In the drawing,

Figure 1 is a schematic circuit diagram of an audio frequency amplifier stage provided with a resistance-capacity coupling network embodying the invention, and

40 Figures 2 and 3 are curves illustrating the operation of the circuit of Fig. 1, the curves of Fig. 2 being audio frequency response curves and the curves of Fig. 3 being reactance curves for certain circuit elements of Fig. 1.

45 Referring to Fig. 1, an audio frequency ampli-

fying channel is shown, wherein an amplifier tube 5 is impedance coupled to a second stage amplifier tube 6, signals being applied to the first stage amplifier 5 through a grid input circuit 7-8, and 5 being derived from the second stage 6, through the usual anode output circuit indicated at 9.

The impedance coupling system is of the resistance-capacity type, comprising an anode output resistor 10, connected in the anode output circuit 11 of the first stage amplifier device 5, and being connected with a positive anode supply lead 12 through a series filter resistor 13. The negative anode potential supply lead may be assumed to be the chassis or ground indicated at 14, for example.

A bypass circuit, forming with the series filter resistor 13, a portion of the filter means in the anode circuit, is indicated by the shunt tuned circuit 16 and the series bypass capacitor 17. The 20 shunt tuned circuit 16 comprises an inductance element 18 and a shunt tuning capacitor 19. The circuit is connected with a tap connection 20 between the anode output coupling resistor 10 and the series anode circuit filter resistor 13. The 25 bypass circuit also includes, between the tuned circuit 16 and ground 14, the serially connected bypass capacitor 17.

The second stage amplifier grid circuit indicated at 21 includes a grid coupling impedance 30 or resistor 22. The latter is connected to a bias potential supply lead 23 through a suitable series filter resistor 24 and the grid circuit is bypassed to the cathode lead indicated at 25, through a bypass or filter capacitor which provides a relatively low impedance path to signals in the frequency range of the amplifier, between the grid resistor 22 and the cathode.

The coupling between the grid circuit 21 and the anode output circuit 11 is provided by the 40 coupling capacitor indicated at 27 which, preferably, is of relatively low capacity. For relatively low frequency response, the product of the capacity of the coupling capacitor 27 and the resistance of the grid resistor 22 should be made substantially equal to the product of the resistance of the output coupling resistor 10 and the effective capacity of the filter elements 17, 18 and 19 to provide relatively broad frequency response in accordance with the circuits shown in the patent 50 referred to hereinbefore.

Referring now to Fig. 2 along with Fig. 1, if the low limit of the frequency range is extended down to a region below 10 cycles, for example, as indicated by the curve 30, the amplifier may 55 "breathe" or provide low frequency "bobbing" or other undesirable response. However, it is desirable to provide a circuit having the substantially flat response curve similar to the curve 30 above a certain low frequency limit such as 30 cycles, 60 for example, while, at the same time, having a relatively low gain below that predetermined frequency limit.

If an attempt is made to lower the low frequency gain below 30 cycles by lowering the reactance of the bypass circuit, as by the use of a 65 single large bypass capacitor at 17 in place of the circuit shown, or by decreasing the capacity of the coupling capacitor 27, the curve indicated at 32 is found to result, indicating a relatively 70 poor response characteristic above the predetermined limit of 30 cycles.

It has been found that the response characteristic of the curve 30 above the present arbitrary limit of 30 cycles, may be obtained while 75 providing the response characteristic of the curve

32 below 30 cycles, by introducing a parallel tuned circuit such as that shown at 16 in the filter bypass circuit. The action of this circuit may best be understood by examining the reactance diagrams of certain bypass circuit elements, the 5 curves of which are indicated in Fig. 3.

In Fig. 3, the curve 34 represents the reactance of a large by-pass capacitor for the anode circuit such as that shown at 16 in the filter bypass circuit. The action of this circuit may 10 best be understood by examining the reactance diagrams of certain bypass circuit elements, the 15 curves of which are indicated in Fig. 3. In Fig. 3, the curve 34 represents the reactance of a large by-pass capacitor for the anode circuit such as that shown at 16 in the filter bypass circuit. The action of this circuit may 10 best be understood by examining the reactance diagrams of certain bypass circuit elements, the 15 curves of which are indicated in Fig. 3.

In Fig. 3, the curve 34 represents the reactance of a large by-pass capacitor for the anode circuit such as that shown at 16 in the filter bypass circuit. The action of this circuit may 10 best be understood by examining the reactance diagrams of certain bypass circuit elements, the 15 curves of which are indicated in Fig. 3. In Fig. 3, the curve 34 represents the reactance of a large by-pass capacitor for the anode circuit such as that shown at 16 in the filter bypass circuit. The action of this circuit may 10 best be understood by examining the reactance diagrams of certain bypass circuit elements, the 15 curves of which are indicated in Fig. 3.

Using the circuit of Fig. 1, the response curve 42 of Fig. 2 was obtained in an impedance coupling network, the constants of which are the same as for obtaining the curve 32 of Fig. 2, but with the addition that the inductance 18 equals 26 henries with a direct current resistance of 860 ohms, with a capacitor 19, of 2.25 microfarads, and with the series filter resistor 13 reduced to 5,000 ohms.

It will be seen that with this circuit the coupling capacitor 27 may be reduced while the bypass capacitor 17 may be increased, without obtaining the undesirable effects of these changes above a predetermined frequency such as 30 cycles, for example, in the range below 100 cycles, while "breathing" and undesired response is cut-off rapidly below that frequency.

Further referring to the reactance curves of Fig. 3, the reactance of a by-pass capacitor alone in a filter network forming part of a resistance-capacity coupling means or network may be represented by the curve 34, while the reactance 50 of the tuned circuit 16 may be represented by the curves 46, and the combined reactance of the series filter capacitor and the tuned circuit is represented by the curves 38-39-40.

Thus, there is substituted for the filter capacitor a reactive network whose apparent capacitive reactance approximates the capacitive reactance of a small capacitor above the frequency of resonance and the apparent capacitive reactance of which approximates the capacitive reactance of a large by-pass capacitor, below the frequency of resonance. It is thus possible to shift from this response curve 30 obtained with a small by-pass capacitor to the response curve 32 obtained with a large by-pass capacitor by decreasing the reactance through the frequency of resonance.

I claim as my invention:

1. In an impedance coupling network for an electric signal amplifier, the combination of a coupling resistor, a filter resistor in series with 70 said coupling resistor, and a bypass circuit for said filter resistor connected between the junction of said resistors and ground, said circuit comprising a series capacity element, an inductance element and a shunt tuning capacity means for 75

5 said inductance element, said circuit elements providing reactance in the bypass circuit approximating that of a relatively small bypass capacitor above a predetermined frequency and the reactance of a relatively large bypass capacitor below a predetermined frequency.

10 2. An impedance coupling network in accordance with claim 1, further characterized by the fact that the inductance element and shunt tuning capacity means provide a shunt tuned circuit in series with said by-pass circuit responsive to a frequency below a predetermined limiting frequency in the response characteristic of said network.

15 3. In an audio frequency amplifier, the combination with a pair of amplifier tubes, of a resistance-capacity network providing impedance coupling means between said tubes, said network including an anode output circuit for one of said tubes, a coupling resistor in said circuit, a filter resistor in series with said coupling resistor, and a bypass circuit for said filter resistor connected between the junction of said resistors and ground, said circuit comprising a series capacity element, an inductance element and a shunt tuning capacity means for said inductance element, said circuit elements providing reactance in the bypass circuit approximating that of a relatively small bypass capacitor above a predetermined frequency 20 and the reactance of a relatively large bypass capacitor below a predetermined frequency.

25 4. In a resistance-capacity interstage coupling network for signal amplifying apparatus and the like, means providing a relatively high uniform frequency response characteristic therein over a wide frequency band, a filter in said network having a series element and a shunt by-pass circuit including a filter capacitor, and means providing a tuned circuit in series with said capacitor, the combined capacitive reactance of the shunt circuit being relatively high above resonance of said tuned circuit to provide a high gain above a predetermined frequency, and the capacitive reactance of the shunt circuit below resonance of said tuned circuit being of a relatively low value sufficient to appreciably attenuate signals in a frequency range below said predetermined frequency.

30 5. In an audio frequency amplifier, the combination of an interstage resistance-capacity coupling network having a coupling resistor in one leg of said network, a series filter element for said leg of the network, and a by-pass circuit connected between said filter element and said coupling resistor, said by-pass circuit including a by-pass capacitor and a parallel tuned circuit in series therewith, the capacitive reactance of said circuit being relatively low below a certain predetermined low frequency and being relatively high above said predetermined frequency.

35 6. A resistance-capacity coupling network including in combination, an output anode circuit comprising branch circuits, one of said branch circuits including an output anode coupling resistor and a filter network in series relation to each other and to the anode circuit, said network including a shunt tuned circuit and a series capacity element, and the other of said branch circuits including a coupling condenser and a load or grid resistor in series relation to each other, the product of the capacity of the coupling condenser and the resistance of the load resistor being substantially equal to the product of the resistance of the first named output coupling resistor and the capacity of the filter network at

40 frequencies above a critical frequency, and the product of the capacity of the coupling condenser and the resistance of the load resistor being substantially less than the product of the resistance of the first named output coupling resistor and the effective capacity of the filter network below the critical frequency.

45 7. In an electric discharge tube amplifier, a resistance-capacity interstage coupling network, comprising in combination, an output anode circuit, an output anode coupling resistor and a filter impedance element in series relation to each other in said circuit, a branch circuit included in said output anode circuit comprising a coupling capacitor and a load resistor in series relation to each other, said coupling and branch circuit elements having a predetermined relation providing a relatively high gain throughout a predetermined frequency response band above a predetermined critical frequency, and a bypass circuit for said filter impedance element comprising a shunt tuned circuit and a series capacity, said circuit having a capacitive reactance for causing a voltage generated by an amplifier device connected with said output circuit to be out of phase with the voltage across said output coupling resistor at frequencies below said critical frequency.

50 8. In a resistance-capacity amplifier coupling network, a coupling impedance, a series filter element therefor and a bypass circuit for said series filter element comprising a shunt tuned circuit and a series capacity, said circuit elements providing a reactive network having an apparent capacity approximating a capacity value for 35 causing said network to respond in a relatively low frequency range with high gain above a predetermined critical frequency and having an apparent capacity which is greater than said first named capacity in a frequency range below said 40 critical frequency.

55 9. In an electric signal amplifier, an interstage coupling network comprising an anode circuit impedance element, a filter circuit in series therewith comprising a shunt tuned inductance and a series capacity element, a coupling capacitor and a load impedance connected in series and forming a branch circuit substantially in parallel with said series connected anode impedance and filter circuit, said coupling elements thereby forming two substantially parallel branch circuits having impedance values such that the product of the resistance of the anode impedance element and the apparent capacity of the filter bypass circuit at frequencies below the resonance frequency of 50 the tuned inductance is materially greater than the product of the resistance of the load impedance and the capacity of the coupling capacitor and the product of the resistance of the anode impedance element and the apparent 55 capacity of the filter bypass circuit at frequencies above the resonance frequency of the tuned inductance is substantially equal to the product of the resistance of the load impedance and the capacity of the coupling capacitor at frequencies 60 above the resonance frequency of said tuned inductance element.

65 10. In a resistance-capacity coupled amplifier, the combination of an output coupling impedance element, a filter element in series therewith, and 70 means providing a bypass circuit for said filter element comprising a capacitor element and a tuned inductance element in series relation to each other, the reactance of said elements being such that the effective shunt capacity of said cir- 75

- cuit increases in response to and attenuates signals below a predetermined critical frequency and that the effective shunt capacity effect of said circuit decreases to a predetermined value for signals in a frequency range above said critical frequency.

11. In an electric signal amplifier, a coupling network comprising resistance-capacity elements and including a coupling impedance across which signals are conveyed, a series filter element therefor, and means providing a shunt bypass circuit for said filter element, the capacitive reactance of which changes with frequency and which comprises a shunt tuned circuit, and a series capacitor providing a capacitive reactance of a predetermined value for signal frequencies above a predetermined critical frequency and having a relatively low capacitive reactance below said critical frequency.
12. A resistance-capacity coupled amplifier including an electric discharge amplifier device and

an output coupling network therefor of the resistance-capacity coupling type, characterized by the fact that the coupling elements including a plate resistor R_p , an output coupling resistor R_g , a coupling condenser C_g , and a tuned filter network comprising a shunt tuned circuit and a series capacity of effective overall capacity C_f are of such related impedance and capacity values that the equation $C_g R_g = R_p C_f$ is substantially satisfied above a critical frequency, and that the expression $C_g R_g < R_p C_f$ is satisfied below that critical frequency, whereby the output voltage across the output coupling resistor is substantially in phase with the voltage generated by said amplifier device at frequencies above the critical frequency and the voltage across the output coupling resistor is out of phase with the voltage generated by said device at frequencies below the critical frequency.
